UNITED STATES PATENT OFFICE.

LAWRENCE A. CLARK, OF CHICAGO, ILLINOIS, ASSIGNOR TO ARCHER IRON WORKS, OF CHICAGO, ILLINOIS, A CORPORATION OF ILLINOIS.

BUCKET FOR HOIST-TOWERS.

1,089,046.

Specification of Letters Patent.

Patented Mar. 3, 1914.

Application filed January 13, 1913. Serial No. 741,671.

To all whom it may concern:

Be it known that I, LAWRENCE A. CLARK, a citizen of the United States, residing at Chicago, in the county of Cook and State 5 of Illinois, have invented a certain new and useful Improvement in Buckets for Hoist-Towers, of which the following is a specification.

My invention relates to improvements for 10 buckets for hoist towers and the like, and relates particularly to such buckets as are used in connection with hoisting towers for handling concrete and the like. In such hoist towers where the material is discharged into a bucket at the bottom of the 15 tower and then drawn by a hoist to an open portion of the tower where it is then dumped considerable difficulties have been met in providing a dumping bucket. The bucket 20 must be held in a vertical position for filling and for its transit to the top of the tower. It must then be tipped over so that the material can be discharged. The operation must be rapid, positive and automatic 25 in such manner that the hoisting engineer can have full control of the hoisting and dumping of the bucket.

Under ordinary circumstances the hoist tower is provided with a pair of guides with- 30 in which slide a so-called bail. This bail carries a bucket which is pivoted at its bottom to the bail or frame and provided with a latch at its top which latch is by suitable mechanism locked at all times except when 35 the bucket is about to be dumped and which is at that time unlocked. This latch, of course, is a more or less complicated piece of machinery very likely to get out of order and likely to be jammed by the concrete. In 40 fact, experience shows that ordinarily when the workmen return to the work of the morning the concrete has to be cleaned out of the latch with a cold chisel and hammer before it can be worked at all.

45 My invention therefore has for its object to substitute for this unsatisfactory latch arrangement a device which will hold the bucket in the vertical position when this is needed but which will freely permit it to be dumped without any difficulty of any kind whatsoever.

My invention is illustrated in the accompanying drawing wherein—

Figure 1 is a side elevation showing the 55 bucket in a vertical or upright position; Fig.

2, a view showing the bucket in the dumping position; and Fig. 3, a section along line 3—3 of Fig. 1 with parts broken away.

Like parts are indicated by like letters throughout the several figures.

The hoist tower A is provided with the guides or rails A¹ between which is slidably mounted the bail or frame A². The cable A³ leads upwardly from the bail over a sheave A⁴ and down to the hoisting engine not shown. The lugs A⁵ on the bail or frame are located upon either side of the track or guide and hold the bail or frame at all times in parallelism with the track.

The fins B project outwardly on one side 70 of the bail adjacent the two guides. In these fins is mounted a shaft B¹ to which is pivoted the bucket B². It will be noted that the shaft is to one side of the bottom of the bucket so as to support the bucket eccentrically the bucket resting when in the upright position upon this bar and also upon the cradle or bracket B⁵ at one end of the bail. The bucket is open at the top and larger at 75 the top than at the bottom. It is provided on one side with the rollers B³ which are located on the same side of the bucket as the bar upon which it is pivotally mounted. These rollers are adapted to engage curved tracks or dumping guides B⁴ rigidly mounted 80 on the tower. When the bucket is at the bottom of its path ready to be filled it assumes the upright position as indicated in Fig. 1 being held in the upright position because it is eccentrically pivoted. When it 85 is hoisted the roller comes in contact with the dumping guides and pulls the bucket away from the bail in the usual manner until the bucket assumes the position shown in Fig. 2 when it dumps into the hopper. As the bail is lowered the bucket will again 90 be forced into the upright position and there held because of its eccentric support. By this arrangement no latch of any kind what- 95 ever is needed. There is no tendency for the bucket to tip over and it is perfectly free at all times to be tipped for dumping when any force greater than the force of gravity is applied to it. This greater force is, of course, the lifting force of the cable pressing 100 the bucket roller against the dumping guide.

It will be evident that, while I have shown in my drawing an operative device, still many changes might be made in size, shape 110

and arrangement of parts without departing materially from the spirit of my invention, and I wish, therefore, that my drawing be regarded as in a sense diagrammatic.

5 I claim:

1. A hoist comprising a slidably mounted rectangular frame means for holding said rectangular frame in vertical position
- 10 a cradle carried by said frame a bucket resting in said cradle a pivotal connection between one side of said bucket and said cradle and located below and to one side of the center of gravity of the bucket and means responsive to the upward movement of the bucket for tilting it.
- 15 2. A hoist comprising a slidably mounted rectangular frame means for holding said rectangular frame in vertical position a cradle carried by said frame a bucket resting in

said cradle a pivotal connection between one side of said bucket and said cradle and located below and to one side of the center of gravity of the bucket and means responsive to the upward movement of the bucket for tilting it said means comprising a contact member adjacent the upper edge of the bucket on the same side as the pivotal connection between the connection and cradle a fixed stop mechanism along the side of the path of the bucket in opposition to said contact member.

In testimony whereof, I affix my signature in the presence of two witnesses this 8th day of January 1913.

LAWRENCE A. CLARK.
